UNITED STATES PATENT OFFICE.

HANS E. TYLANDER, OF CRYSTAL LAKE, ILLINOIS, ASSIGNOR TO FORD, JOHNSON & CO., OF MICHIGAN CITY, INDIANA.

MACHINERY FOR WEAVING CANE.

SPECIFICATION forming part of Letters Patent No. 243,012, dated June 14, 1881.

Application filed December 6, 1880. (No model.)

To all whom it may concern:

Be it known that I, HANS EMANUEL TYLANDER, of Crystal Lake, in the county of McHenry, in the State of Illinois, have invented 5 certain new and useful Improvements in Machinery for Weaving Cane, which are fully set forth in the following specification, reference being had to the accompanying drawings, in which—

- 10 Figure 1 is a side elevation of my improved loom and stretcher, the front of the loom appearing at the right of the figure. Fig. 2 is a transverse section on the line $x\ x$ in Fig. 1, looking backward. Fig. 3 is a transverse section on the line $y\ y$ in Fig. 1, also looking backward. Fig. 4 is a transverse section on the line $z\ z$ in Fig. 1, looking forward. Fig. 5 is a detailed view of a piece of the fabric produced by the loom. Fig. 6 is a detailed and enlarged 15 section taken between the back pair of standards of the loom, so as to show the farther or right-hand standard in side elevation and the rollers in section. Fig. 7 is a detailed and enlarged elevation of a part of one of the stretching-rollers in connection with its ratchet-wheel, 20 crank, and spring-pawl. Fig. 8 is a detailed and enlarged plan view of one of the brackets and one end of one of the supporting-strips of the stretcher. Fig. 9 is a detailed and enlarged 25 rear elevation of the gage by which the squares are spaced. Fig. 10 is a cross-section of the same. Fig. 11 is a detailed and enlarged elevation of one of the two similar frames of harness. Fig. 12 is a cross-section of the same on the 30 line $v\ v$ in Fig. 11. Fig. 13 is a detailed and enlarged front elevation of the upper portion of the beater or sley. Fig. 14 is a top view of the crosser for interweaving the diagonal strips with the fabric shown in Fig. 5. Fig. 15 35 is an end elevation of the same. Fig. 16 is a front elevation of the same. Fig. 17 is a section on the line $w\ w$ in Fig. 14. Fig. 18 is a side view of the shaft or blade of the needle, a considerable part of its length nearest the 40 handle being broken off. Fig. 19 is a detailed and enlarged top view of the tip or bent end of the needle-blade. Fig. 20 is a detailed view of a piece of the fabric and the needle-tip in 45 the process of finishing.

The same letters denote the same parts in 50 all the figures.

My invention relates to mechanism for the weaving of strips of cane and similar textile material into fabrics—such, for example, as are used for chair-seats.

It consists in a beater or sley to straighten the successive strands of the woof, the distance to which the beater can be drawn forward against the strands being regulated by cords connecting it with a weighted roller which tends 60 to turn in such a direction as to shorten the cords, but which is held stationary by the engagement of spring-paws with a series of teeth set on its circumference at equal intervals corresponding to the desired length of the checks 65 or open spaces in the fabric, and the spring-paws being so arranged that the operator can disengage them at pleasure.

It consists, still further, in a stretcher, capable of use separately or in combination with 70 the loom, on which the fabric may be stretched and finished.

It consists, also, in a crosser having an eye at the tip or point and one or more rollers, by 75 means of which the tip is turned downward and upward through the interstices of the web, so to intertwine the diagonal strands therewith; and it consists, further and more particularly, in the several devices and combinations of devices which will be fully described hereinafter, 80 and definitely pointed out in the claims.

In the drawings, A denotes the standards, of which there are two at the back of the loom or farthest from the operator. These support, near their upper ends, a roller, B, on which 85 the strips of cane for the warp are wound, the length of these strips corresponding to the desired length of the web, strips as cut from the cane being spliced end to end when necessary to give the requisite length. In order that all 90 the cane on the roller may be woven without waste, I prefer, instead of attaching the cane directly to the roller, to attach to the roller one end of a sheet of canvas, b^5 , equal in length to the distance from the standards A to the opposite pair of standards, C, where the interweaving of the woof begins, and attach the strips which are to form the warp to the other 95

end of this canvas. The number and arrangement of these strips are governed by the desired breadth and closeness of the fabric. The warp-roller B is turned so as to wind the cane (or 5 canvas and cane) upon it by means of a crank, b, at one end. Around the other end of roller B, which projects a little beyond the supporting-standard, is a friction-belt, b', connected by a cord, b², with a lever, b³. This lever is 10 pivoted at one end to the standard A, which supports the belted end of the roller. Its other end rests on one of the pins b⁴, which project from the corresponding standard, C. These pins b⁴ are so placed that when the lever rests 15 between the upper one and the second the cord (which is fastened to the lever at some little distance from the fulcrum) will not draw on the belt. When, however, the lever is shifted to the pin next below, the belt is tightened, so 20 as to prevent the turning of the roller B.

A short distance below the warp-roller B the standards A support another roller, D, to which is attached one end of a sheet of canvas, d, (shown in Fig. 2 and, by dotted line in 25 Fig. 1,) of length about equal to the length of web to be woven. The direction of this canvas, as it lies wound on the roller from the fastened to the free end, is downward and forward. The cane-strips for the warp are wound on the 30 roller B in the opposite direction, the free end of the canvas d being first inserted (and, if need be, fastened, though this will not ordinarily be requisite) between the layers of the canvas on the warp-roller B. The canvas d 35 will thus be unwound from its roller and wound upon the warp-roller between the layers of cane-strips, so as to prevent any tangling of the latter, and secure a continuous and even unrolling of them during the operation of weaving. Obviously the unrolling of the cane-strips will also unroll the canvas d from the 40 warp-roller. In order that it may at the same time be rolled up again on its own roller, D, a cord, d', of suitable length is attached at one 45 end to D, so as to wind upon it with the un-winding of the canvas. To the other end of this cord is attached a weight, d², which will tend to unwind it as soon as the pull upon the canvas ceases. I prefer to attach such a cord 50 and weight to each end of the roller D, which is provided with suitable flanges or grooves to receive it. In order that the weight may not interfere with other parts of the machinery, I pass the cord over a pulley, d³, at each end of 55 a shaft, turning in brackets a little in front of the roller D, and provide an opening in the floor, so that the weight may descend as far as the length of the cord will allow; or the pulley might be attached to the ceiling, the cord 60 being, of course, lengthened so as to provide for the increased distance of the pulley from the roller D.

Just above the warp-roller, and resting on it, is another roller, E, having its bearings in the 65 standards A, preferably a little in front of B, so as to bring a larger portion of its surface in

contact with the cane-strips as they are unwound from B. That the roller E may rise as the roll of cane on B grows thicker, a slot, a, is cut vertically in each standard A, above the 70 bearing of the roller E.

Upon that smaller part of roller E which turns in the standard is fitted a block, e, which projects to the right and left of the standard, and has its projecting parts wider than the slot, 75 so as to hold it in its place. The upper surface of this block is flat, and has attached to it the lower end of a coiled spring, e', the upper end of which is fastened in like manner to a block, e², having its lower surface flat, but 80 otherwise resembling the block e, and arranged, like it, to play up and down in the slot a. Upon the upper surface of this block bears the lower end of a set-screw, a', which turns in the standard A, above the slot. The spring 85 causes the roller E to press on the cane as it is unwound from the warp-roller, thereby keeping it taut and even. The intensity of this pressure is regulated by the set-screw. The front pair of tall standards C carry on their 90 tops a shaft, e, over which, in grooves, one near each end, pass two cords, c', by which are suspended vertically the front harness, F, and the back harness, F'. Each set of harness consists of a rectangular frame, f, in which are set 95 a number of upright bars, f', of equal breadth and at equal distances apart. This breadth is determined by the degree of fineness of the cane that is to be used, and varies ordinarily from one-quarter to three-eighths of an inch. 100 The distance of the bars apart is just enough to let the strands of cane pass freely between them. The bars are so arranged that those of the one frame are opposite the intervening spaces of the other. Each bar is pierced at f² 105 horizontally from front to rear, and midway between its upper and lower ends, so as to allow a strand of cane to pass readily through it. Each frame of harness is connected by a pair of cords, f³ or f⁴, attached to its lower corners, with a treadle, F² or F³, the length of each frame sufficiently exceeding the breadth of the web to leave room between the two cords of each pair for the web to pass. This arrangement is best shown in Fig. 4 of the drawings. The operator, sitting on the bench G, is 110 able to reach the treadles with his feet, and, by depressing them alternately, to depress alternately the front harness, F, and the back harness, F', the depression of one necessarily 115 raising the other absolutely as well as relatively, on account of their being connected by the cords c'.

The beater or sley H consists of a frame, h, similar in general shape to the frame f of the harness, and a row of wires, h', detachably set in it similarly to the bars of the harness, their thickness and their distance apart being determined by the degree of fineness of the cane which is to pass between them. The upper 125 bar, h², of the frame is detachably set on the side bars, so as to admit of readily changing

the wires. The beater is supported on a pair of bars or arms, h^4 , the upper ends of which are set in the lower bar, h^3 , of the frame h , while their lower ends are pivoted at h^5 to the base of the loom. These arms have a forward curvature a short distance below the frame h , in order to clear the roller I , which is placed below the beater, and at the same time hold the beater just in front of the harness-standards C . The lower bar, h^3 , of the frame h projects at each end beyond the rest of the frame far enough to lock against the standards C and prevent the beater swinging back between them. A cord, j , attached near each of the lower corners of the frame h , has its other end attached to the gage-roller J , which turns in bearings attached to the short middle standards, K . This cord is just long enough to pass under the gage-roller and reach to the forward pair of short standards L , so as to allow the beater to be drawn forward thus far.

On the circumference of the gage-roller, about midway of its length, are set a row of cogs or double row of pins, j' , at equal distances apart in the row, determined by the distance which it is desired to leave between the pairs of strands in the woof. A short standard, K' , not tall enough to touch the roller, is set directly under the pins j' . On the front and back of this standard are set a pair of springs, j^2 and j^3 . As shown in the drawings, Figs. 9 and 10, each spring is a flat bar of metal bent above the top of the standard K' into the general form of an arch, so as to bring the upper end between two of the cogs or pairs of pins j' . This upper end is again bent backward, so as to form a hook, which fills the space between the two pairs of pins, its back or closed part being toward the roller, and its upper side forming a flat bearing for the upper pair of teeth or pins. The springs are connected by rods j^4 or j^5 with a treadle, J' , whose forward end is side by side with those of the harness-treadles, within reach of the operator's foot. Each of the springs j^2 and j^3 is prevented from being drawn back too far by a stiff loop-spring, k' , the ends of which are set in the upper end of the standard K' , between the springs j^2 and j^3 , while the bent middle portion passes outside, or on the convex side of the spring j^2 or j^3 which it is to support.

To the roller, a little the other side of the middle from the pins j' , is attached one end of a weighted cord, j^6 , which is wound around the roller so that the weighted end of the cord hangs in front of the roller, the weight thus turning the roller (when it is released from the hold of the springs) in such a direction as to wind the cords j upon it, and thus shorten the range through which the beater H can be drawn forward. The forward spring, j^2 , has its connection with the treadle far enough in advance of that of the back spring, j^3 , (the distance being about eight inches in the machine with which I have made my experiments,) to make it unclosed a little before the back spring

does, the latter (inasmuch as it interferes obliquely with the tooth below it,) operating to retard though not arrest the turning of the roller, so that the operator taking his foot 70 immediately from the treadle, the forward spring has to catch again in the next notch. The short standards L , next to the operator's bench, support on their tops a roller, l , over and around which the woven fabric passes, so 75 as to change its course from forward to backward. The roller I , which is supported on the harness-standards C , below the beater, is provided at one end with a crank, i , a ratchet-wheel, i' , and a pawl, i^2 , so that the web may be wound 80 on it when it is not desired in the same process to carry it back to the stretcher for finishing, otherwise the web passes under this roller, over the roller k^2 supported on the tops of the standards K , under the roller a^2 mounted on the 85 standards A , near the base, under and around the roller N' mounted on the tops of the back standards M' of the stretcher, and thence forward again over and around the front roller, N , supported on the front standards, M , of the 90 stretcher, on which it is finally wound.

The front standards, M , of the stretcher are shown in the drawings as made in one piece with the back standards, A , of the loom, and this construction will be most convenient when 95 the intention is to finish the web on the stretcher as fast as it is woven on the loom; but these two portions of the machinery may be made entirely separate from each other. Each of the rollers, N and N' , of the stretcher has the 100 portion n or n' of its periphery at one end toothed, and is provided at the same end with a crank, n^2 or n^3 . A spring-pawl, n^4 , attached to each standard, below the toothed periphery n or n' , and consisting of a flat bar of spring 105 metal having its lower portion bolted in a vertical position to the standard, and its middle portion twisted so as to bring the upper portion into a plane at right angles to that of the lower, the direction of the side edges being 110 still vertical, engages with the teeth n or n' , so as to prevent any backward turning of the roller when the operation of the crank has ceased. When, however, it is desired to turn the roller in the opposite direction the eccentric disk m , which is pivoted on the standard 115 below the toothed periphery, is turned so as to bring that part of the circumference which is farthest from the pivot in contact with the spring-pawl n^4 , which is thus necessarily forced 120 back and disengaged from the teeth of the roller. The roller N is detachably set on its standards M , so that when one piece of the finished fabric has been wound on it the roller can be removed and replaced by another. The 125 roller I of the loom may also be set detachably on its standards for the same purpose when the loom is used separately from the stretcher.

On the inner faces of the standards M and M' are set brackets O , each consisting of two 130 parts, the first, o , being a flat bar bent into the form of an L , the horizontal member be-

ing uppermost, so as to form a level bearing-surface, having its length toward the other end of the stretcher, and the upright member being fastened by a screw-bolt, o' , to the standard. A slot in the upright member makes it 5 adjustable in height. On the upper surface of the horizontal member of bar o , near its farther end, is set the second part, o^2 , of the bracket, which is a flat bar having its length 10 at right angles to that of the horizontal member of bar o , to which it is attached, near its outer end, by a screw-bolt, a slot, o^3 , making its position adjustable to the right or left. On its inner end—*i. e.*, the end toward the other 15 side of the stretcher—the bar o^2 supports one end of a bar or rail, o^4 , whose other end rests on the corresponding bracket at the opposite end of the stretcher. The office of these rails is to support the edges of the web during 20 the process of finishing. The rail is attached to its bracket at each end by a pin or bolt, and is made adjustable longitudinally by being perforated with several bolt-holes at different points of its length, so that when the 25 roller at either end of the stretcher has the greater part of the web wound on it the rails may be shifted toward the other end, so as not to come in contact with the roll. The crosser which is used for intertwining the diagonal 30 strands with the web produced by the loom is shown in Figs. 14, 15, 16, 17, 18, and 19. It has a shaft or blade, P , of suitable length to pass through the frame Q , in which it has its bearing, and to reach from side to side of the 35 web in a direction diagonal to its squares or spaces.

The frame Q is preferably made of cast-iron, and consists of a pair of side bars, q , upright when the needle is in operation, connected at 40 their ends by a pair of shorter cross-bars, q' and q^2 , the space between them being open. The upright side bars are considerably thinner from front to rear in the middle than toward the ends. The whole frame may be 45 made in one piece. A handle, R , by which the frame is carried, is affixed to the upper cross-bar, q' , so as to be nearly horizontal when the crosser is in operation. It is also secured to the lower cross-bar, q^2 , by a brace, r . The 50 upper cross-bar, q' , has a cylindrical perforation passing through it from end to end, which affords a bearing for the needle-blade P . At one end this perforation is enlarged to receive one end of a hollow shaft, s , the other end of 55 which is supported in a hanger, q^3 , secured by screws to the top of the frame Q . The needle-blade passes through this hollow shaft, and is made fast in it by a set-screw, s^2 , so as to turn with the shaft. The shaft s has rigidly 60 affixed to it a pinion, S , whose teeth engage with those of another wheel, S' , whose diameter is two or three times as great. This latter wheel is rigidly affixed to a shaft, s' , which turns partly in semi-cylindrical recesses in the 65 faces of the side bars, q , and partly in cleat-boxes attached by screws to the faces of the

side bars, the object of this special construction being to make the shaft s' , like s , readily detachable from the frame. The other end of the shaft s' also projects beyond the bar q , and 70 has rigidly affixed to it a driving wheel or crank, S^2 , by which it is turned, thus communicating a rapid rotary motion to the pinion S , and consequently to the needle-blade P . The blade P is cylindrical in shape for the greater part 75 of its length; but at the point it is flattened, as shown in Fig. 19 of the drawings, and pierced with an eye, p' , broad near the point of the blade, so as readily to receive and release the strips of cane, and narrower below, 80 so as to hold the strip firmly in the operation of intertwining it with the web. The flattened part p of the blade is bent slightly, so as to change the plane of the flattened surface, as shown in Fig. 18 of the drawings, the bend 85 being sufficient to bring the tip successively above and below the strands of the web as the blade revolves.

A belt might be substituted for the teeth, by which the motion of the wheel S' is communicated to wheel S ; but the construction described will ordinarily be found preferable. 90

To put the machinery in operation, the cane-strips, their number and distance apart being determined by the desired breadth and closeness of the web, are wound on the roller B alternately with the canvas d in the manner already described. Their free ends are then drawn forward through the harness, one strip passing through a bar of the back harness and 95 between two bars of the front harness, and the adjoining strips between two bars of the back harness and through the opposite bars of the front harness, one or more bars in each frame being skipped for every one that is used, the 100 number skipped varying, according to the desired breadth of the open squares in the web. Guiding-strings attached to the front ends of the cane-strips must be passed between the wires of the beater, around the roller l , under 105 the roller I , over l^2 , under a^2 , around the back roller, N' , of the stretcher, and over the front roller, N , to which they are secured, the course being indicated by dotted lines in Fig. 1. If, 110 however, the loom is to be used separately from the stretcher, it will be sufficient to pass the strings around the roller l and secure their ends to the under side of I . The rod b^3 is then set in its highest rest on the side of the right-hand standard, C , so as to relax the belt b' 115 and allow the roller B to turn. The operator, sitting on the bench G , begins by drawing the forward ends of the warp-strands up to the roller l . He then draws the first strand of the 120 woof across between the strands of each pair in the warp, advantageously using as a shuttle a stick long enough to reach across the warp, the cane being caught in a slot in one end of the stick. A shed for the passage of the woof is formed in the usual way by pressing the 125 treadle F^2 or F^3 , and thus lifting one frame of harness with its strands while depressing the 130

other. The first strand of the woof being drawn through, the operator draws the beater H forward against it the full distance permitted by the cords j connecting the beater with the gage-roller J. The beater is then thrust back again, the other treadle, F^3 or F^2 , is depressed, so as to reverse the positions of the two sets of harness and the warp strands which they respectively carry, and the second strand of the woof is drawn through in the opposite direction to the first, and straightened with the beater in the same way. Then on thrusting back the beater the operator depresses the treadle J' , so as to unlock for an instant the springs j^2 and j^3 , so as to permit the gage-roller J to turn the distance between two pairs of pins j' , and thus shorten the cord which limits the forward sweep of the beater by the distance which is to be maintained between the corresponding strands in the successive pairs which constitute the woof. The operator taking his foot off from the treadle immediately, the springs close again so as to catch in the next notch of the gage-roller. In this way the formation of the web is continued, its progress from the roller l, where the weaving is completed, to the roller N or I, on which it is wound, being secured by turning N or I, as the case may be, by means of its crank, this being conveniently done by an assistant. The front end of the web, in the condition shown in Fig. 5, having come upon the stretcher, the work of finishing or intertwining the diagonal strands begins. The finisher, taking the handle of the crosser in one hand, pushes the blade diagonally across the web over the warp and under the woof, or vice versa, at the same time turning the blade with the other hand by means of the driving-wheel S^2 , so that the bent end p is turned upward to pass over one set of strands and downward to pass under the other. When the bent end projects beyond the farther edge of the web the operator threads it by drawing one end of a strip of cane through the wider part of the eye p' and a little way beyond, so as to give it a hook-like turn, and then wedging it in the narrower part of the eye. He then draws the crosser back through the same course without turning the blade, and thus intertwines the cane diagonally with the web, the strips of course being carried over the warp and under the woof, or vice versa, in the path previously made by the upward and downward turning of the bent tip p of the blade, as shown in Fig. 20 of the drawings. In this way the web is finished with a rapidity far beyond anything attainable by the ordinary methods.

What I claim as my invention, and desire to secure by Letters Patent, is—

1. In a loom, a roller having teeth set at uniform distances apart around its periphery for a part of its length, in combination with a spring-pawl arranged to lock between the teeth by its own elasticity, mechanism under the control of the operator for drawing the pawl from between the teeth, a weight arranged to turn the roller whenever the pawl is

unlocked, the beater or sley, and cords connecting the roller with the beater or sley and arranged to wind around the roller when it is turned by the weight, substantially as and for the purposes described.

2. The gage-roller J, provided with the pins j' , weighted cord j^6 , the spring-pawls j^2 and j^3 , the treadle J' , the supporting-springs k' , the rods j^4 and j^5 , the beater H, and the connecting-cords j , all constructed, arranged, and operating in combination, substantially as described.

3. A stretcher to hold the web during the process of finishing and roll it up when finished, consisting of two corresponding pairs of standards, two rollers, each supported by one pair, and provided at one end with a set of teeth on its periphery, a pawl on each pair of standards arranged to engage with the toothed periphery, mechanism for holding the pawls disengaged, a pair of rails for supporting the edges of the web, and brackets projecting from the standards, for supporting said rails, all in combination, substantially as described.

4. The standards M and M', the rollers N and N', toothed at n and n' , and provided with cranks n^2 and n^3 , the spring-pawls n^4 , eccentric-disks m , rails o^4 , and supporting-brackets attached to the standards, all constructed, arranged, and operating in combination, substantially as described.

5. The standards A and C, roller B, belt b' , cord b^2 , rod b^3 , rests b^4 , roller D, provided with the sheet of canvas d and weighted cords d' , pulleys d^3 , roller E, adjustably set in the standards A, springs e' , harness F and F', treadles F^2 and F^3 , pivoted beater H, toothed gage-roller J, provided with the weighted cord j^6 , spring-pawls j^2 and j^3 , treadle J, rods j^4 j^5 , cords j , and roller I, provided with the crank i , pawl i^2 , and ratchet-wheel i' , all in combination, substantially as and for the purpose described.

6. The standards A and C, roller B, belt b' , cord b^2 , rests b^4 , rod b^3 , adjustable therein, roller D, provided with the sheet of canvas d , and weighted cords d' , pulleys d^3 , roller E, adjustably set in the standards A, springs e' , harness F and F', treadles F^2 and F^3 , pivoted beater H, toothed gage-roller J, provided with the weighted cord j^6 , spring-pawls j^2 and j^3 , rods j^4 and j^5 , treadle J' , cords j , rollers l, I, k^2 , and a^2 , standards M and M', rollers N and N', toothed, as described, and provided with cranks and adjustable pawls, brackets O, and rails o^4 , all in combination, substantially as and for the purpose described.

7. A separate and portable crosser, consisting of a frame, a straight-shafted blade arranged to revolve therein, and a system of wheels and shafts set in the frame, whereby the blade is made to revolve by the operator at the same time that he is pushing it through the fabric, substantially as and for the purpose described.

8. A separate and portable crosser provided

with a straight-shafted blade bent and perforated, as described, at the forward end, in combination with mechanism controlled by the operator for causing the blade to revolve during its passage through the fabric, substantially as and for the purpose described.

9. The frame Q, handle R, revolving shafts s and s', gear-wheels S and S', driving-wheel

S², and blade P, affixed to the shaft s, and provided with the bent and flattened tip p, and the eye p', all in combination, substantially as and for the purposes described.
